ATTORNEYS.

UNITED STATES PATENT OFFICE

CHARLES W. DAKE, OF CHICAGO, ILLINOIS, ASSIGNOR TO THE PYLE-NATIONAL COMPANY, OF CHICAGO, ILLINOIS, A CORPORATION OF NEW JERSEY

LAMP STAND

Application filed November 13, 1930. Serial No. 495,341.

My invention relates to improvements in lamp stands and especially relates to a stand and focusing device for use in connection with locomotive headlights. Experience has shown that lamp filaments on locomotive headlights are exceedingly sensitive to vibration and many failures result. It is desirable to cushion the lamp therefore. There is no point to cushioning the housing or the reflector because of the great weight involved and because of the relative rigidity and durability of the parts and I have provided therefore a cushioning device which permits the necessary range of focusing adjustment and which is compact and durable.

My invention is illustrated more or less diagrammatically in the accompanying drawings, wherein—

Figure 1 is a vertical section through a part of the housing and reflector showing the light and supporting parts in elevation;

Figure 2 is a rear end elevation of the lamp support;

Figure 3 is a perspective detail of a part of the bracket;

Figure 4 is a perspective detail of the cushion.

Like parts are indicated by like characters throughout the specification and drawings.

A is a supporting base. Mounted on it by means not here shown is a searchlight housing A¹. This housing contains a reflector A² apertured at A³, the housing being apertured at A⁴ in line with the aperture A³. The reflector is mounted at its mouth in the housing and the housing is supported at its forward end on the base A by any suitable mechanism not here shown since it forms no part of the present invention.

B is a bracket bolted to the base A. This bracket contains a stud B¹, there being a lug in the bracket to engage the keyway B² in the stud B¹ so that the stud may move vertically with respect to the bracket but is held against rotation with respect thereto. A lug B³ projects from the bracket and has threaded in it the thumb screw B⁴ which thumb screw engages the gate B⁵ pivoted on one side of the bracket, the bracket being cut away to permit the gate to engage the stud B¹, to lock the stud

against longitudinal movement. The stud B¹ is threaded at B⁶ at its upper end, carries a supporting pad B⁷ and is associated with an adjusting nut B⁸ which nut is supported by the bracket. This nut may be rotated to raise or lower the stud and the thumb screw B⁴ may be operated to lock the stud against displacement, the adjusting nut being operative for displacement of the stud only when the thumb screw is released. This provides a vertical adjustment of the electric light bulb. Mounted on the pad B⁷ are two flexible cushion blocks C of rubber or suitable shock absorbing resilient material. Screws C¹ C² hold these two blocks on the pad B⁷, the two blocks being arranged with their axes generally parallel with the axis of the reflector. Screws C² C² associated with each of the cushion blocks tie them to ears C³ on the split socket C⁴, the axis of which is parallel with the axis of the reflector housing and perpendicular to the axis of the bracket. This split socket is provided with ears C⁵ and thumb screw C⁶ whereby the socket may be clamped on the electric light holder C⁷.

The electric light holder C⁷ carries the electric light bulb D and power is provided for the bulb through the conductors D¹. An ear D² on the holder C⁷ is in threaded engagement with an adjusting screw D³, which screw is also in threaded engagement with an ear D⁴ on the split socket C⁴. When the thumb screw C⁶ is released the screw D³ may be rotated by the thumb piece D⁵ to move the electric light holder longitudinally. Since the adjusting screw D³ has two threads a very fine adjustment is provided and danger of jarring loose is minimized. These two adjustments are all that are needed to bring the light into proper focus, that is, the light must be moved up vertically into the plane of the axis of the reflector and must then be moved longitudinally along the axis of the reflector for focusing. There is no need of a lateral adjustment because that can be taken care of by the original manufacturer of the device.

The two flexible cushion pads providing as they do, two rather widely separated cushion supports with the pads tying the two parts together furnish an adequate flexible base for

the electric light and cushion the blows resulting from the irregularities of the track, vibration of the engine and the like. At the same time since the pads are permanently anchored between the supporting base and the split socket, there is no tendency toward escape and no opportunity for the parts to get out of working adjustment.

The relative position of the plate B⁷ beneath the socket and the connection between this plate and the ears C¹ and C³ at points out of line with the supporting lug B¹ and screw B⁶ makes it possible for the flexible support to be interposed between the socket and the lamp bracket without increasing the overall height of the bracket support and lamp, thereby making it possible for the adjustable support and the socket to be used interchangeably in a lamp bracket with sockets of the uncushioned type so that the cushion feature may be added to lamps already in existence without change whatever in lamp bracket, reflector or housing.

I claim:

- 25 1. A support for electric light holders in combination, a bracket, a stud longitudinally adjustable in said bracket, means for locking said stud in adjusted position, a split socket, a lamp holder supported in said socket and longitudinally movable therein, means for longitudinally adjusting said holder in said socket, means for locking said holder in adjusted position, and cushioning means interposed between said stud and socket, said cushioning means being fastened to said stud by certain fastening bolts and to said socket by other fastening bolts and constituting the sole connection of said socket to said stud.
- 30 2. A support for a locomotive headlight including in combination, a bracket, a stud longitudinally adjustable in said bracket, a pad carried by said stud, a split socket, a lamp holder carried by said socket and longitudinally adjustable therein, cushioning means interposed between said pad and said socket, fastening means securing said cushioning means to said pad, other fastening means securing said cushioning means to said socket, said cushioning and fastening means constituting the sole connection of said socket to said pad and providing a resilient connection therebetween, a threaded lug forming a part of said socket, a threaded lug on said holder, the threads of said lugs being different and a screw having two threaded portions one of which engages the lug on the holder and the other of which engages the lug on the socket for adjusting said holder in said socket.
- 35 3. Signed at Chicago, county of Cook and State of Illinois, this 10th day of November, 1930.

CHARLES W. DAKE.
